JAMES C. SIDNEY, OF PHILADELPHIA, PENNSYLVANIA.

Design No. 4,080, dated May 31, 1870.

DESIGN FOR AN UMBRELLA-STAND.

The Schedule referred to in these Letters Patent and making part of the same

I, JAMES C. SIDNEY, of Philadelphia, in the county of Philadelphia and State of Pennsylvania, have invented and produced a new and original Design for an Umbrella-Stand, of which the following is a specification.

The novelty of my invention consists in making an umbrella-stand in the shape of a partially opened umbrella, mounted on a suitable base, as is fully shown in the annexed drawing, in which—a a a, &c., represent the usual ribs and tips of an umbrella;

b b b, &c., the folds of the covering material, as they appear when an umbrella is partially opened.

c, an ornamental handle; and d, the base.

I claim as my invention—

The design for an umbrella-stand, as described and shown.

J. C. SIDNEY.
